UNITED STATES PATENT OFFICE.

RUSSELL S. ALLINE, OF CLEVELAND, OHIO.

DISPENSING DEVICE.

Application filed June 9, 1922. Serial No. 567,005.

To all whom it may concern:

Be it known that I, RUSSELL S. ALLINE, a citizen of the United States, and a resident of Cleveland, county of Cuyahoga, and State of Ohio, have invented a new and useful Improvement in Dispensing Devices, of which the following is a specification, the principle of the invention being herein explained and the best mode in which I have contemplated applying that principle, so as to distinguish it from other inventions.

The present invention relates to a device for holding a box of soap and dispensing the same, together with towels and more particularly to a device which can be conveniently attached to an automobile or the like, so that it will be inconspicuous and so arranged that boxes of cleansing soap may be inserted in and removed from the device and be readily available for use, together with paper towels. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a central vertical section through the device; Fig. 2 is a sectional view on the line 2—2 of Fig. 1; and Fig. 3 is a perspective view of a portion of the edge of the box showing the turned down ears in dotted line; Fig. 4 is a perspective view of a modified form of holding member; Fig. 5 is a broken sectional view of the form shown in Fig. 4; Fig. 6 is a view similar to Fig. 5 but showing a modification; Fig. 7 is a fragmentary elevation of another modified form of can holding means; Fig. 8 is an elevational view partially in section of another modification; Fig. 9 is a sectional view of a modified form; and Fig. 10 is a sectional view of another form of can holding member.

In the form shown in Figs. 1 to 3 the present device consists of a holding member comprising an annular ring 1 provided with a horizontally extending annular flange 2 and this holding member is securely attached to a supporting bracket 3 by means of rivets 4 or the like, the bracket having a depending

end 5 provided with apertures 6 adapted to receive screws 7 or the like to hold the bracket and holding member to the automobile frame or other fixed body 8 to which it is to be attached.

This annular holding member is of such a size as to snugly receive the ordinary type of round tin box or can 9, in which the usual cleansing soap 10 is packed and in order to mount the box or can of soap in the member, it is slipped in from the bottom and the can is provided with ears 11 which are punched so that they can be bent outwardly at right angles to the plane of the wall of the can, into the position shown in dotted lines in Fig. 3, when the can will be supported by these ears on the horizontal flange of the holding member, as shown in Fig. 1.

Mounted on the holding member is a cover 12 of considerable depth, which is hinged as at 13 to the member above the bracket and this cover is adapted to completely enclose the top of the can and has an outwardly turned flange 14 around the bottom adapted to rest on the horizontal flange of the holding member. At the front of the device, the cover is provided with a spring clip 14 having its lower end 16 rebent so as to engage below the horizontal flange on the holding member and thus lock the cover in its closed position. The downwardly extending end 16 of this clip is adapted to be used as a means for disengaging the clip and for lifting the cover so as to present the open soap can to the user. Within the cover is mounted a spring 20 which is preferably formed of wire, although a flat spring may of course be employed, the ends being attached by rivets 21 or the like to the rear inner surface of the cover and being then coiled as at 22 and extending toward the front of the cover in a flat loop 23 which normally tends to spring toward the top of the cover. Folded napkins or towels, preferably paper, are adapted to be placed in the cover between the spring and the top of the cover and will thus be readily available when the cover is opened.

In Figs. 4, 5 and 6, a modified form of holding member is shown in which the annular ring 31 and flange 32 are split, the ends 33 of the ring being bent outwardly and being provided with aligned apertures 34 to receive a clamping bolt 36. As shown in Fig. 5 the ring may be clamped below the rib 37 of the can or the ring may be pro-

vided with a complementary groove 38 to receive the can rib 37 as shown in Fig. 6.

In Fig. 7 another modification is shown in which the ring 41 is provided with slots 42 in which are received pins 43 attached to the cans, the slots having horizontal portions to lock the can against vertical movement. A slightly different form is shown in Fig. 8 in which both the can top 50 and the ring 51 are threaded so that the can may be screwed tightly into the ring. In the form shown in Fig. 10, the holding member is a box or can 55 of a size to receive the soap can, while in Fig. 9 the same construction is employed as shown in Figs. 1 and 2 but here the ring 1 is small enough so that the can must be inserted from the top, the can rib 37 engaging with the flange 2 to hold the can in place.

The present devices are particularly adapted to be used on automobiles or other places where space is limited, and are adapted to receive cans of cleansing soap of the type used to remove grease or the like from the hands of the user and more particularly a soap to be used without water, so that the present device consists of a holder and can which can be readily attached to a fixed body and which will be inconspicuous and which will furnish the necessary soap as well as towels. In all of the forms, a holding member is provided which is adapted to removably receive and securely hold a can of soap in place, the holding member being provided with an easily operable cover which holds the towels which are easily removable as soon as the cover is opened.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a device of the character described, the combination of a holding member adapted to receive and hold a can, means for attaching said member to a fixed body, and a cover for said member, said cover being provided with towel holding means.

2. In a device of the character described, the combination of a holding member adapted to receive and hold a can, means for attaching said member to a fixed body, and a cover for said member, said cover being

hinged to said member and being provided with a resilient means adapted to retain towels within said cover above the can.

3. In a device of the character described, the combination of a holding member comprising an annular portion adapted to receive a can, means on said annular portion and can adapted to engage to removably hold said can in said member, a cover for said can and means in said cover for holding towels above the can.

4. In a device of the character described, the combination of a holding member adapted to receive a can, means for attaching said member to a fixed body, and a cover for said member, said cover being hinged to said member and being provided with a resilient means adapted to retain towels within said cover above the can and a spring clip on said cover and adapted in the closed position of said cover to engage with said holding member to lock said cover in its closed position.

5. In a device of the character described, the combination of a holding member comprising an annular ring having a horizontal annular flange, a soap containing can adapted to snugly fit within said ring and having cut ears adapted to be bent downwardly over said horizontal flange to removably secure said can in said ring, and a cover pivotally attached to said holding member, said cover being provided with a spring adapted to retain paper towels in said cover, means for locking said cover to said holding member in closed position and a bracket attached to said holding member for attaching said device to a fixed body.

6. In a device of the character described, the combination of a holding member comprising an annular ring having a horizontal annular flange, a soap containing can adapted to snugly fit within said ring and having cut ears adapted to be bent downwardly over said horizontal flange to removably secure said can in said ring, and a cover pivotally attached to said holding member, said cover being provided with a spring attached at the rear side of the cover and extending across the same and adapted to retain paper towels between said spring and the interior of said cover, and a spring clip on the front of said cover adapted to engage with the horizontal flange of said holding member to lock said cover in closed position.

Signed by me this 7th day of June, 1922.

RUSSELL S. ALLINE.
